UNITED STATES PATENT OFFICE.

AUGUST SCHLAK, OF BROOKLYN, NEW YORK, ASSIGNOR TO JOHN F. MEYER, OF CHICAGO, ILLINOIS.

AMUSEMENT DEVICE.

Application filed March 16, 1927. Serial No. 175,752.

This invention relates to amusement devices and its object is to provide novel means adapted to be operated by a coin to furnish fun and entertainment or instruction depending upon the information with which the machine is supplied to be disclosed by the operation of the coin.

A further object of the invention is to provide a machine of novel construction which is adapted to disclose one of a series of sections on a display plate depending upon the set of the plate and the movement of the coin.

The invention has other objects in view which will appear hereinafter in the detail description, reference being made to the drawings showing a selected embodiment of the invention, and referring to which:

Fig. 1 is a front elevation of a machine embodying the invention.

Fig. 2 is a detail enlarged view showing one section of the display plate disclosed to view by the operation of a coin.

Fig. 3 is a horizontal sectional view on the line 3—3 of Fig. 1.

Fig. 4 is a rear elevation of the operating mechanism set in one position for operation by a coin, the cabinet being shown in section.

Fig. 5 is an enlarged section of the coin tripper mechanism in set position.

Fig. 6 is a view similar to Fig. 5 with the tripper mechanism tripped by the coin.

Fig. 7 is a view similar to Fig. 4 showing the parts in a different position.

Fig. 8 is a sectional view on the line 8—8 of Fig. 7.

Fig. 9 is a rear elevation of the operating mechanism showing the parts as they appear in Fig. 7 except that one tripper has been operated by a coin.

Fig. 10 is a transverse sectional view on the line 10—10 of Fig. 9.

Fig. 11 is a transverse sectional view on the line 11—11 of Fig. 9.

Fig. 12 is a detail perspective view of one of the trippers.

Fig. 13 is a detail perspective view of the display plate.

Fig. 14 is a detail perspective view.

Referring to the drawings the invention comprises a cabinet 1 of suitable construction having an open front and a front plate 2 provided with a central opening 3 and a plurality of coin openings 4 arranged in a transverse row above the opening 3. A supporting plate 5 is mounted on the back of the

front plate 2 and it is provided with two inclined ribs 6 beneath the coin openings 4 to receive the coins inserted through the openings. The ribs cause the coins to roll inwardly to the vertical center of the supporting plate and then to slide down the face of the plate, being interrupted by a plurality of obstructions in the form of lugs 7 on the face of the supporting plate. In Fig. 1 I have indicated the possible travel of a coin 8 in broken lines. Near the bottom of the supporting plate there are a plurality of openings 9 separated by ribs 10 having arrow shaped upper ends 10'. A transparent glass plate 11 is mounted in the front plate to close the opening 3 therein and cover that part of the supporting plate which would otherwise be exposed through said opening. Means hereafter described are provided for supporting the coin temporarily in one of the openings 75 9, as shown in Fig. 5 and for releasing the coin so that it may drop through the slot 12 between the front plate and the supporting plate into the bottom of the cabinet. The front plate carries the supporting plate and the latter carries all of the operating mechanism except the pointer 13 so that access may be readily had to the mechanism by removing the front plate. Therefore, I have made this front plate easily removable by engaging the lower end of the front plate with a shoulder 14 at the bottom of the cabinet and by providing a lock 15 at the top of the front plate, on the back thereof, to engage a keeper on the inside of the top of the cabinet. The side edges 2' of the front plate overlap parts of the cabinet (Fig. 7) and when the front plate is secured in place it completely closes the open front of the cabinet.

The pointer 13 is mounted rigidly on a shaft 13' which projects through the front plate and carries a segment 16 rigid thereon. The pointer is adapted to be moved between the stops 17 (Fig. 1) to register with any one of the lugs 18. These lugs are disposed to indicate corresponding sections on the front plate, (defined in a general way by broken lines on Fig. 1) and these sections are supplied with legends, symbols or other suitable matter which it is not necessary to show in order to fully understand the invention.

Segment 16 is provided with an arm 19, and a link 20 is pivotally connected at one end to this arm and at its other end to a display plate 21. This plate is provided at its edges 110

with flanges 22 which slidably engage the guides 23 fastened to the back of the front plate. By manipulating the pointer 13 the segment is caused to swing on its pivot 13' and move the display plate 21 up and down behind the openings 9 in the supporting plate. The sections of the display plate (indicated by broken lines) may be supplied with verses, legends, symbols or anything suitable for display through individual openings 9. In Fig. 13 I have shown the display plate provided with a variety of symbols but this is merely for the purpose of illustrating one possible use of the invention. Ordinarily I propose 15 to print short sentences on the display plate so that one of them will be disclosed through any opening 9 which may be exposed.

A plurality of trippers 24 are arranged to slide between lugs 25 on the back of the supporting plate. Each tripper 24 (Fig. 12) is bowed outward at 26 and has a longitudinal slot 27 and a hook 28 at the lower end of the slot. A spring 29 is engaged with a prong 30 formed on the supporting plate, and extends through the slot 27 and is engaged with the hook 28 (Figs. 4, 6). The tendency of this spring is to hold the tripper normally in up position, as shown in Figs. 4 and 6, and to return the tripper to upward position when 30 it is released from down position as shown in Figs. 5 and 14. The lower end of the tripper is widened to provide a sort of shutter 31 which substantially covers the opening 9 and that portion of the display plate behind said opening. The tripper is bent slightly at 32, at the top of the shutter 31, to set the shutter forwardly with respect to that portion of the tripper immediately above the shutter, so that the upper edge 33 of the shutter may engage the top edge 34 of its opening 9 when the tripper is in lowered position.

The segment 16 is provided with a plurality of pins 16' which are arranged to engage crossed cam arms 35 pivoted at one end 36 on the supporting plate and projecting outwardly close to the side edges of the supporting plate and are there connected with a setting yoke 37 which crosses the trippers and is held in guides 38 on the back of the face plate 50 2. The setting yoke is arranged to engage lips 39 struck up from the trippers and when the segment is moved by operating the pointer the yoke will be depressed to move the trippers downward and engage all of the shutters 55 in position in the openings 9 for concealing the display plate and the matter thereon. In the same operation, it may here be noted, the display plate is raised or lowered to a position which will be indicated by the pointer with 60 certain display matter registered behind the openings 9 to be displayed when any one of the trippers is released and returned to up position (Fig. 6).

Each of the shutters 31 is provided with a finger 31' which projects forwardly into a

position close to the glass plate 11 into the path of a coin 8 which may travel down into the pocket formed by two ribs 10', Fig. 1. The coin will strike the finger 31' and release the shutter from its closed position, whereupon the coin will travel down through the slot 12 into the cabinet and the tripper will slide upward under the influence of spring 29 leaving the opening 9 unobstructed so that the operator may see whatever appears on 75 the display plate within the range of the opening 9.

I may apply the display matter directly upon the plate 21 or, as shown in Fig. 13, I may provide a card 21' bearing the display matter and removably engaged with beads 21" on the plate so that the card may be changed from time to time as desired. The display matter on this card will be arranged in sections which I have indicated in broken 80 lines on Fig. 13. These sections are arranged in series extending transversely of the card and there are as many sections in a series as there are openings 9 in the supporting plate, and there are as many series as there are sections and lugs 18 on the front plate. It will be observed that the series of display sections on the display plate corresponding to the particular lug 18 with which the pointer is registered will be arranged in register with the 85 openings 9 in the supporting plate, but these openings will be closed by the shutters 31 until a coin releases a shutter to uncover the opening and disclose the display section registered therewith. Whenever the pointer is 90 released from one position to another all trippers in released position are operated to close the shutters at the same time that the display plate is shifted so that only those display sections of the display plate which have 95 been uncovered through the operation of a coin or token of some kind will be displayed to the operator since the shutters remain in closed position until they are released by the operation of a coin. The trippers slide 100 against the back face of the supporting plate underneath the setting yoke and the latter is held in engagement with the trippers by the guides 38 so that the fingers 31' on the trippers are always positioned in the path of 105 the coins to be engaged thereby for releasing the trippers and uncovering the openings. While it is expected that the pointer will be shifted to a new position after each operation by a coin this is not necessary because 110 another coin may travel into another pocket and release another tripper to open another shutter and disclose another section on the display plate. But every time the pointer is shifted the display plate will be shifted and 115 all the shutters will be closed. The legends indicated by the lugs 18 may be in the form of questions and the display matter on the display plate may be in the form of printed 120 answers to these questions. The answers may 125 130

be humorous and of a nature to afford fun and amusement to the operator. I have shown and described the supporting plate as made separately from the front plate, but it may 5 be integral with the front plate.

Other changes in the form, construction and arrangement of parts may be made without departing from the spirit and without sacrificing the advantages of the invention 10 and I reserve the right to make all such changes as fairly fall within the scope of the following claims.

I claim:

1. A coin operated machine comprising a 15 plate having a plurality of openings therein, a vertically movable display plate disposed behind said openings, vertically movable shutters for closing said openings, and means for closing said shutters and setting said display 20 play plate in a predetermined position.

2. A coin operated machine comprising a 25 plate having a plurality of openings therein, a display plate movably disposed behind said openings, said display plate having display sections thereon arranged in a plurality of series, the sections in each series being disposed correspondingly to said openings, means for setting said display plate with any 30 one series of display sections registering with said openings, and means for closing said openings when the display plate is set.

3. A coin operated machine comprising a 35 plate having a plurality of openings therein, a display plate movably disposed behind said openings, said display plate having display sections thereon arranged in a plurality of series, the sections in each series being disposed correspondingly to said openings, shutters for closing said openings, and means 40 operable for closing all of said shutters and resetting said display plate.

4. A coin operated machine comprising a 45 plate having a plurality of openings therein, a vertically movable display plate disposed behind said openings, vertically movable shutters for closing said openings, and a pointer accessible at the front of the machine for setting said display plate in a predetermined position and at the same time closing 50 said shutters.

5. A coin operated machine comprising a 55 plate having a plurality of openings therein, a display plate slidably disposed behind said openings, shutters for closing said openings, a movable pointer accessible at the front of the machine, and means at the back of said plate operated by said pointer for closing said shutters and setting said display plate.

6. A coin operated machine comprising a 60 plate having a plurality of openings therein, a vertically movable display plate disposed behind said openings, an independent vertically movable shutter for closing each opening, means at the back of the plate for closing, any open shutter and for setting the dis-

play plate, and a movable device at the front of the machine for operating said means.

7. A coin operated machine comprising a 70 plate having an opening therein, a slidable display plate disposed behind said opening and having a plurality of display sections thereon, a shutter movable parallel to the display plate for closing said opening, means for holding said shutter in closed position, and means adapted to be operated to release 75 and move the shutter to open position.

8. A coin operated machine comprising a 80 plate having an opening therein, a display plate movably disposed behind said opening and having a plurality of display sections thereon, a tripper slidable on the back of said plate, a shutter carried by said tripper and adapted to close said opening, means for engaging the shutter in closed position, means adapted to be operated to release the shutter, 85 means for retracting the shutter when released, and means operated from the front of the machine for closing said shutter and for setting said display plate.

9. A coin operated machine comprising a 90 plate having an opening therein, a display plate movably disposed behind said opening, a spring controlled tripper slidable on the plate and comprising a shutter to close said opening, means for holding the shutter in 95 closed position, means adapted to be operated to release the shutter and means adapted to be operated at the front of the machine for closing the shutter and at the same time shifting the display plate. 100

10. A coin operated machine comprising a plate having an opening therein, a display plate movably disposed behind said opening, a tripper slidable on the back of the plate and comprising a shutter adapted to close said opening, means for holding the shutter in closed position, means on the shutter adapted to be operated to release the shutter, a spring for pulling the shutter away from said opening to disclose the display plate, and means 105 operated at the front of the machine for shifting said display plate and for closing said shutter when the display plate is shifted. 110

11. A coin operated machine comprising a 115 plate having an opening therein, a display plate behind said opening, a slidable shutter for closing said opening, said shutter having a shoulder to engage an edge of the opening for holding the shutter in closed position, means for releasing the shutter, means for withdrawing the shutter from closed position, and means for returning the shutter to closed position. 120

12. A coin operated machine comprising a 125 plate having an opening therein, a display plate movably disposed behind said opening, a slidable tripper comprising a shutter adapted to close said opening, said shutter being offset to enter said opening and having a shoulder thereon to engage an edge of the 130

opening for holding the shutter in closed position, means adapted to be operated for releasing the shoulder, a spring for retracting the shutter when released, and means adapted 5 to be operated from the front of the plate for moving the tripper to close the shutter.

13. A coin operated machine comprising a plate having an opening therein, a display plate movably disposed behind said opening,

10 a tripper comprising a shutter for closing said opening, means for holding the shutter in closed position, a finger on the shutter adapted to be operated to release the shutter, means for retracting the shutter from closed position, and means for returning the shutter to closed position.

14. A coin operated machine comprising a plate having a plurality of openings therein, a display plate movably disposed behind said 20 openings, a separate tripper comprising a shutter for closing each opening, means for holding the shutters in closed position, means adapted to be operated for releasing the shutters, means for retracting the shutters to disclose the display plate and cam means for 25 moving said trippers to close said openings.

15. A coin operated machine comprising a

plate having a plurality of openings therein, a display plate movably disposed behind said openings, a pivoted arm connected with the 30 display plate, and means for operating said arm to move said plate behind said openings for displaying different portions thereof, a series of individually operated shutters for said openings, and means for operating said 35 shutters.

16. A coin operated machine comprising a plate having a plurality of openings therein, a display plate movably disposed behind said 40 openings, shutters for closing said openings, trippers carrying said shutters, and cam devices adapted to be operated to move said trippers for closing said openings.

17. A coin operated machine comprising a plate having a plurality of openings therein, a display plate movably disposed behind said 45 openings, movable trippers comprising shutters for closing said opening, a cam operated yoke for moving said trippers to close said shutters, a segment for operating said yoke, 50 a link connecting said segment to said display plate for shifting said plate, and means for operating said segment.

AUGUST SCHLAK.
